COMBINED TOY HOUSE WITH MOVABLE FIGURES THEREON

Joseph V. Ferriot, 965 Nokomis Drive, Akron, Ohio

Filed Nov. 20, 1961, Ser. No. 67,586

Term of patent 3½ years

(Cl. D34—15)

FIG. 1

FIG. 2

FIG. 3

FIG. 1 is a front elevation of a combined toy house with movable figures thereon, showing my new design;

FIG. 2 is a top plan view thereof;

FIG. 3 is a right side elevation thereof;

The back of the toy house is flat and plain.

I claim:

The ornamental design for a combined toy house with movable figures thereon, as shown and described.
